DESIGN FOR A VEHICLE DOOR HANDLE

Burton S. Floraday, Toledo, Ohio, assignor to Detroit Harvester Company, Detroit, Mich., a corporation of Michigan

Application September 18, 1941, Serial No. 103,398

Term of patent 7 years

To all whom it may concern:

Be it known that I, Burton S. Floraday, a citizen of the United States and a resident of Toledo, Lucas County, Ohio, have invented a new, original, and ornamental Design for a Vehicle Door Handle, of which the following is a specification, reference being had to the accompanying drawing, forming a part thereof.

In the drawing:

I claim:

The ornamental design for a vehicle door handle, as shown.
